2 SHEETS—SHEET 2.

UNITED STATES PATENT OFFICE.

CESAR CASTRO, OF NEW YORK, N. Y.

INTERNAL-COMBUSTION ROTARY MOTOR.

1,178,131.

Specification of Letters Patent.

Patented Apr. 4, 1916.

Application filed March 22, 1913. Serial No. 756,268.

To all whom it may concern:

Be it known that I, CESAR CASTRO, a citizen of Ecuador, residing at New York, New York county, and State of New York, have 5 invented and discovered certain new and useful Improvements in Internal-Combustion Rotary Motors, of which the following is a specification.

My said invention consists in an improved 10 construction of rotary explosive engines, or motors, wherein a series of explosions in a series of cylinders on a common shaft are arranged to follow each other in rapid succession during the rotation of the motor and 15 serve to maintain the speed and power of the motor as may be desired, and it consists further in various improvements in the construction and arrangement of parts, whereby an efficient motor of this character is 20 provided, all as will be more fully hereinafter described and claimed.

Referring to the accompanying drawings, which are made a part hereof and on which similar reference characters indicate similar 25 parts, Figure 1 is a view, partly in front elevation and partly in section, showing a 4-cylinder motor constructed in accordance with my said invention, Fig. 2 a view, partly in end elevation and partly in cross section, 30 showing the interior construction, Fig. 3 a detail view on an enlarged scale showing the parts adjacent to an explosion chamber on an enlarged scale, and Fig. 4 a detail view of one of the sliding cut-offs.

35 In said drawings the portions marked A represent the external stationary casing; B the internal rotary structure; and C the radial pistons.

The external casing A is a heavy casing, 40 of suitable strength for the purpose, formed with hollow peripheral walls constituting a water jacket surrounding the various cylinders. A circulation of water is provided for by means of suitable water inlets, such 45 as shown at 10, and suitable water outlets, such as shown at 11. Said casing is of appropriate diameter and of the length to provide for the number of cylinders required for an engine of the power desired. In Fig. 50 1 I have shown four cylinders, but it will be understood that any number, more or less, may be provided, according to the requirements.

The rotary structure B is mounted upon 55 the main shaft 13 and consists of a heavy rim of sufficient strength for the purpose,

supported by spokes 14 from a central hub 15, which is keyed to said shaft. Said rotary structure B may be a unitary structure extending from end to end of the motor or 60 engine, or, as will be readily understood, it may be composed of sections properly joined together and mounted within the outer casing A. The joints between said internal rotary structure and stationary external casing are preferably formed by interengaging 65 grooves and flanges as shown most clearly in Fig. 1. Said connections are slidable so that the rotary structure will rotate freely within the stationary structure which is 70 rigidly and securely mounted upon a suitable base or frame, not shown, as from side supports A'. In Fig. 1 the intermediate joints are shown as composed of heavy rims a having overlapping edges, the rims being 75 bolted to the internal structure and overlapping annular flanges on the sides of the sections of casing A. It will be understood, of course, that the particular details of construction may be varied and that, as shown, 80 the structure is merely a suitable form to illustrate the broad idea of the invention comprising the relative arrangement and general construction of parts whereby the 85 operation and result desired are secured.

At intervals, preferably on diametrically opposite sides of said rotary structure, sliding pistons 16 are mounted in radial grooves or sockets therein, being normally held outward, with their faces bearing against the 90 inner face of the casing A, by means of springs 17 which are mounted within said pistons and bear at one end against the inner ends of said sockets and at their outer ends against cross bars forming a part of said 95 pistons. Packing strips 18 are mounted in the faces of said pistons as shown. Extending back from each piston for a distance the surface of said rotary part is formed flat, or extends tangentially to the circumference, forming for a short distance a wider 100 space between the periphery of the rotary structure and the interior surface of the casing. Said casing A is correspondingly formed at points on opposite sides and these 105 portions of the chamber are designed for the explosion chambers, indicated in Figs. 1 and 3 by E. An inlet valve 19 leading from the carburetor, or mixture supply, is located at one end of said explosion chamber E and 110 a spark 20 of any appropriate type is located in juxtaposition thereto. A sliding

cut-off plate 21 is mounted in the radial socket with piston 16, on the front side thereof, and is normally held extended by springs 22 which are interposed between the inner 5 ends of the legs of said plates and the bottom of said socket. Another sliding cut-off plate 23 is mounted in the combustion chamber head, adjacent to the explosion chambers, and is also adapted to slide out and in 10 and is held in normal contact with the surface of the rotary structure B under spring pressure. A spent gas exhaust 25 is provided just at the end of the working chamber close to the entrance to the combustion 15 chamber.

I will term each part of the rotary structure serving as one side of a piston chamber and the part of the casing A in which it revolves as a "cylinder" and, as before 20 stated, it will be understood that such cylinders may be as many or as few as required to secure the power desired for the motor. The explosion chambers E are spaced around each cylinder. In the structure shown there 25 are two of such explosion chambers in each cylinder and four cylinders. The explosion chambers of the different cylinders are, however, located at different points predetermined degrees apart around the circumference of the structure.

In operation, the parts being constructed and assembled as shown and described, and shaft 13 being set in motion, by any cranking mechanism, as in other types of explosive engines, pistons 21 of the several 35 "cylinders" passing along the chambers between rotary structure B and the casing A will meet the inclined cut-off portion 26 of the interior walls of said casing and be 40 forced inward in a radial direction until they pass under the dividing bridge-wall 27, which is located to be in practical contact with the periphery of rotary structure B and to cut off any communication between the 45 explosion chamber and the section of the chamber behind said bridge-wall, which is the exhaust end of the working chamber. Sliding cut-off plate 23 serves to prevent communication between the two parts at this 50 point. As said rotary structure B revolves each sliding cut-off plate 21 passes under the bridge-walls 27 of the appropriate cylinders and as soon as they pass said bridge-walls springs 22 force them outward into 55 contact with the internal face of the casing A, and cause a suction, creating a vacuum in the respective explosion chambers behind each plate 21. As soon as piston C is released it also slides outward into contact 60 with the surface of casing A, furnishing a solid and substantial inner end to the explosion chamber of the worm shown in Fig. 2. The sparking mechanism is timed to 65 create a spark when the piston shall have reached the position substantially as shown

in said Fig. 2, and causes an explosion of the charge drawn in through valve 19 by the suction above described. Said piston and the rotary structure are carried forward under the impulse of the explosion. In the 70 construction shown it will be seen that an explosion takes place on diametrically opposite sides of each cylinder simultaneously, the two explosions balancing the strain on the structure and directing their force in 75 a uniform direction against their respective pistons and carrying the rotary structure forward under the power thus generated. Two like explosions will take place in the adjacent cylinder at points a predetermined 80 degree from the points at which the first explosions take place, and so on throughout the series of cylinders comprising the motor, so that at each revolution of the motor as many explosions can be provided for as required to generate the power needed. As 85 each piston approaches the succeeding explosion chamber, it forces the spent gases ahead of it through the exhaust ports 25, thus keeping the working chambers clean 90 at all times. The motor may be kept cool by a constant circulation of water in the water jacket formed in the outer casing, as before described.

It will be understood, of course, that various modifications in the details of construction and arrangement of parts may be made without departing from my invention, which consists, broadly, in the structure of a motor wherein several rotary structures mounted 100 on a single shaft are acted upon successively in chambers arranged in a series to maintain a continuous impulse in a uniform direction. While I show a construction adapted for two explosions in each chamber, as before stated, this can be modified as desired, or found necessary, in order to accomplish 105 the desired result.

Having thus fully described my said invention, what I claim is new and desire to 110 secure by Letters Patent is:

1. A rotary explosive engine comprising a casing having an annular internal chamber, a bridge-wall mounted on the casing, a rotor operable within said chamber, sliding cut-off plates mounted on said casing and rotor respectively and coöperable therewith to form a chamber to receive the explosive mixture, a piston carried by the rotor radially movable into the explosive chamber, and an igniting means located in said explosive chamber, substantially as set forth.

2. A rotary explosive engine comprising a casing having an annular internal chamber, bridge-walls mounted on the casing, a rotor operable within said chamber, sliding cut-off plates mounted on said bridge-walls operable to engage the rotor, sliding cut-off plates mounted on the rotor operable to engage the casing, and said sliding plates with 125

- the casing and rotor providing chambers to receive the explosive mixture, pistons carried by the rotor immediately adjacent the rotor sliding plates and operable to move radially into the explosive chambers, and ignition means located in said explosive chambers, substantially as set forth.
3. A rotary explosive engine comprising a casing having a tangential projecting portion and a bridge-wall, and formed with an annular internal chamber, a rotor operable within said chamber, a cut-off plate slidably mounted in the bridge-wall and operable to engage the rotor, a cut-off plate slidably mounted on the rotor and operable to engage the casing, said plates with the tangential projecting portion and the bridge-wall providing a chamber to receive the explosive mixture, a piston carried by the rotor immediately adjacent the rotor sliding plate and radially movable into the explosive chamber, and an ignition means located in said explosive chamber, substantially as set forth.
4. A rotary explosive engine comprising a casing having a plurality of annular internal chambers, each of said chambers having a diametrically opposed pair of tangential projecting portions and bridge-walls, rotors operable within said chambers respectively, cut-off plates slidably mounted in said bridge-walls and operable to engage the rotors, cut-off plates slidably mounted on the rotors and operable to engage the walls of the chambers, said plates with the tangential projecting portions and bridge-walls providing chambers to receive the explosive mixture, pistons carried by the rotors immediately adjacent the rotor sliding plates and radially movable into the explosive chambers, and an ignition means located in each of said explosive chambers, substantially as set forth.
5. A rotary explosive engine comprising an external casing having an internal annular chamber, said chamber being divided into parts by bridge-walls and extending on one side of said bridge-wall tangentially to the circumference thereof and on the other side being curved from the interior face of said bridge-wall to the normal interior face of the casing, a rotor within said casing, radially-sliding pistons mounted in said rotor, the surface of said rotor being formed to extend tangentially for a distance back from each of said pistons, substantially as set forth.
- In witness whereof, I have hereunto set my hand and seal at Washington, District of Columbia, this twenty-third day of January, A. D. nineteen hundred and thirteen.
